Albert Wanner, Jr.

BY
John W. Wanner,
ATTORNEY.

UNITED STATES PATENT OFFICE.

ALBERT WANNER, JR., OF NEW YORK, N. Y.

FITTING-STOOL.

1,301,203.

Specification of Letters Patent. Patented Apr. 22, 1919.

Application filed April 14, 1916. Serial No. 91,068.

To all whom it may concern:

Be it known that I, ALBERT WANNER, Jr., a citizen of the United States, residing at New York city, in the county of New York 5 and State of New York, have invented certain new and useful Improvements in Fitting-Stools, of which the following is a specification.

The object of this invention is to provide 10 a fitting stool, that is to say, an article of furniture on which one person may rest his foot while having shoes fitted, for example, and the person fitting the shoes may sit, which shall be simple and strong in construction, artistic in appearance, and possess certain other advantages, such as providing a suitable receptacle in which to keep within the convenient reach of the person occupying the seat order books, button 15 hooks, shoe horns and other similar implements.

My invention is characterized by a pair of 20 separate parallel arched bentwood basal side members each bent to substantially the form 25 of the curve of a conic section and having one side of its arch arranged at a gradual incline and the other more precipitate, and means, rigidly connecting said members, including a seat arranged on the high parts 30 and a foot rest arranged on the gradual incline parts of their arches; I prefer to form the foot rest as a receptacle having an opening adjoining the seat.

In the accompanying drawings,

35 Figure 1 is a perspective view of the improved fitting stool;

Fig. 2 is a longitudinal sectional view thereof; and,

40 Fig. 3 is a plan view showing a part of the foot-rest broken away.

The base in the illustrated construction includes two bent-wood side members *a a* arranged preferably to converge in plan (such convergence being simply a contribution 45 to the artistic appearance of the stool, but being otherwise not especially material) and formed arched in side elevation in such manner that one end, as *a'*, of each member approaches the floor or other surface on 50 which the stool rests at more or less of a right angle whereas the other end portion *a''* is inclined so as to approach said surface at a more or less sharp acute angle.

These members *a a* are joined by a seat 55 structure *b* and a box or receptacle *c*.

The seat structure *b* may include two side

standards *d*, each in the present instance being a plate of wood suitably shaped to present the desired artistic effect and having a horizontal straight top edge *e* and a concave bottom edge *f*, the shape of which conforms with the convex upper rear surface of the corresponding side member *a*. Said seat structure also includes the seat proper *g*. The standards *d* may be secured to the 60 side members *a* and the seat proper *g* to the side standards in any approved way, such as doweling, gluing, or by the use of screws, and the like.

The receptacle *c* is preferably constructed 70 as follows: *h h* designates side standards of any form suiting some approved design. These rest respectively upon the side members *a a* in their inclined forward portion *a'' a''*. Resting upon said side standards is 75 a plate of wood *i* forming the foot-rest proper. The top edges of the side standards being inclined when assembled with the members *a a* as shown, the foot-rest proper *i* is also inclined, the angle of inclination being one that is suitable and comfortable to the person who, assumed to be sitting in a chair, has his foot resting on the foot-rest proper. Between the forward 80 end portions of the standards *h* and connecting them and the members *a* is an upright plate of wood *j*, which extends from the lower edges of the members *a* to the foot-rest proper *i*. The standards *h*, the foot-rest proper *i* and the plate *j* form the top, 85 side and forward walls of the box or receptacle, the bottom wall of which, *k*, is preferably composed of laminated plates of wood having their grain crossed (the idea being to make the bottom strong and proof 90 against warping) and is set into opposite longitudinal grooves *l* in the members *a*, being glued or otherwise secured therein. The box is open at the back, as indicated at *m* in Fig. 2, so that the person occupying 95 the seat of the fitting stool may have ready access to his order book and such other articles as may be kept in the box. To impart a finish to the back of the bottom wall *k* of the box, and also to brace the members 100 *a a*, I provide the cross-piece *n*, which may be suitably secured, as by doweling, to said members and the standards *h*.

A cross-piece *o*, to brace the rear portions 110 of the members *a*, is also preferably provided, being doweled into or otherwise secured to said members.

The seat proper *g* and foot-rest proper *i* may be upholstered or padded, as at *p*, or left plain. *g* is a ridge of some suitable material attached to the front portion of the foot-rest proper and serving as a heel support.

Having thus fully described my invention, what I claim as new and desire to secure by Letters Patent is:

- 10 1. An article of manufacture of the class described consisting of a pair of separate parallel arched bentwood basal side members each bent to substantially the form of the curve of a conic section and having one side of its arch arranged at a gradual incline and the other more precipitate, and means rigidly connecting said members including a seat arranged on the high parts and a foot rest arranged on the gradual-incline parts
- 15 2. An article of manufacture of the class described consisting of a pair of separate parallel arched bentwood basal side members each bent to substantially the form of the curve of a conic section and having one side of its arch arranged at a gradual incline and the other more precipitate, and means rigidly connecting said members including a seat arranged on the high parts
- 20 30 and a foot rest arranged on the gradual-incline parts of their arches.

being a receptacle having an opening adjoining the seat.

3. An article of manufacture of the class described consisting of a pair of separate 35 parallel arched bentwood basal side members each bent to substantially the form of the curve of a conic section and having one side of its arch arranged at a gradual incline and the other more precipitate, and 40 means rigidly connecting said members including a seat arranged on the high parts and a foot rest arranged on the gradual-incline parts of their arches, said seat having concave underneath surfaces resting upon 45 and conforming in contour with said basal side members along their line of greatest curvature.

4. An article of manufacture of the class described consisting of two substantially 50 counterpart upright side elements each including an arched portion shaped to substantially the form of the curve of a conic section and having one side of its arch arranged at a gradual incline and the other 55 more precipitate, in combination with a foot-rest member and a seat member connecting said elements and arranged respectively over the gradual-incline and high parts of their arched portions.

In testimony whereof I affix my signature.
